UNITED STATES PATENT OFFICE.

JOSEPH GRANZ, OF DULUTH, MINNESOTA.

RHEOSTAT.

Application filed April 11, 1921. Serial No. 460,464.

To all whom it may concern:

Be it known that I, JOSEPH GRANZ, a citizen of Czechoslovakia, and a resident of Duluth, in the county of St. Louis, State of Minnesota, have invented certain new and useful Improvements in Rheostats, of which the following is a specification.

This invention relates more particularly to that type of rheostats used in connection with the smaller forms of electric motors and the like to control the operation of the same, and the present improvement has for its object,

To provide a structural formation and association of the rheostat parts, whereby the resistance wire or filament having an extended or lengthy nature is effectively supported in a small and compact compass with a very efficient exposure to permit the escape of heat from such resistance wire during actual use.

To provide a simple and efficient construction and arrangement of parts whereby the frictional stress of the adjustable contact shoe upon the resistance winding during an adjusting operation can be materially relieved while electric contact is still maintained, all as will hereinafter more fully appear.

30 In the accompanying drawings:-

Fig. 1, is a front elevation of the present rheostat structure.

Fig. 2, is a sectional elevation on line 2—2 Fig. 5.

35 Fig. 3, is a similar view on line 3—3 Fig. 5.

Fig. 4, is a fragmentary elevation of the movable contact shoe, resistance element and accessory parts and showing in dotted lines 40 the contact shoe in a tilted or released condition.

Fig. 5, is a transverse sectional elevation on line 5—5, Fig. 2.

Fig. 6, is a central transverse section on 45 line 6—6 Fig. 1.

Like reference numerals indicate like parts in the several views.

Referring to the drawings, 1 and 2 designate counterpart marginally flanged heads 50 between which an orificed cylindrical shell 3 is arranged to constitute the ventilated enclosing housing of the present structure.

4 designates a bar or strip of insulating material fixed to the rearward housing head 55 2, and adapted to support the resistance element, terminal posts and other parts of

the appliance in proper insulated relation as hereinafter described in detail.

5 designates the inner and main supporting member or core of the resistance member which in the present construction is of an open skeleton construction and consists of a pair of flat plate metal sections of a split ring shape as shown in Figs. 2 and 3, secured together in properly separated relation by a series of connecting posts or stud 6, with the inner plate metal section attached to the aforesaid insulating bar or strip 4 by screws or other like fastening means as shown in Figs. 3 and 5, to afford the sole supporting means for the resistance member and associated parts.

7 and 8 designate the terminal or binding posts of the appliance and which preferably form extensions of the above mentioned attaching screws by which the inner plate metal section 5 is secured in place. One of said terminal posts 7 is in direct electrical connection with said inner plate member, while the other terminal post 8 has insulated relation to said plate member by means of an insulating washer or bushing of the usual form.

9 designates covering layers or sheets of insulating material of a flat ring shape corresponding with the inner plate metal sections 5 of the resistance member, with each plate metal section having an individual layer or sheet 9, and with each sheet or layer 9 provided with inside and outside flanges or rims 10 and adapted to enclose the edges of an associated plate metal section 5 and prevent electric contact between the same and the resistance winding hereinafter described. In the present construction as shown in Fig. 6, the sheets or layers 9 are arranged respectively, upon the forward face of the outermost plate metal section 5, and upon the rear face of the innermost plate metal section 5.

11 designates the resistance winding, which in the present construction comprises a wire wound around the insulating supporting member or core above described, with its respective ends in electrical connection with the terminal posts 7 and 8.

12 designates a sector shape plate or bridge fixedly secured to a plate metal section 5 and extending inwardly to the center of the appliance to provide support for the adjustable contact number.

13 designates a journal bushing fixedly se-

cured to the plate or bridge 12 in central relation to the other parts of the appliance and formed at its outer end with a lateral sector shaped stop lug 14 arranged in the 5 path of the hereinafter described carrying arm of the movable contact member, to limit the turning movement of the same in either direction.

15 designates the carrying shaft of the 10 movable contact member of the appliance, provided with an operating handle 16 at one end, and arranged to have a turning movement in the bore of the bushing 13, and in addition a limited sliding movement in said 15 bore. Such sliding movement is effected in one direction by an outward pull on the part of the operator upon the handle 16, while a movement in the other direction, and one intended to yieldingly hold the movable contact 20 member and stationary contact member in effect electrical connection, is effected by a spring 17 arranged between a plate metal section 5 aforesaid and a bearing collar 18 secured to the shaft 15 as illustrated more 25 particularly in Figs. 4 and 6.

19 designates a radially arranged arm, the inner end of which is fixedly attached to the shaft 15, while its outer end forms a pivoted support for the contact shoe of the 30 appliance.

20 designates the contact shoe, preferably of a triangular form as shown, pivotally mounted on the outer end of the arm 19, with one of its flat faces adapted to have extended sliding contact with the windings of 35 resistance wire 11 above described.

21 designates a spring associated with the shoe 20 and in its arm 19, with a tendency to impart a tilting movement to said shoe as 40 illustrated in dotted lines in Fig. 4, so that when the carrying arm 19 and associated parts are drawn outward by the operator as above set forth, one end of the shoe 20 will be maintained in electrical contact with the 45 resistance winding 11 by the influence of said spring.

Having thus fully described my said invention what I claim as new and desire to secure by Letters Patent, is:—

50 1. In a rheostat, the combination of an enclosing housing, an insulating base secured within the same, a resistance support secured to said base and comprising a pair of core plates of a split ring form attached together in spaced relation, a winding of resistance wire wound upon and from one to the other of said core plates, and a centrally pivoted arm carrying at its outer end a contact shoe adapted for bearing upon said 55 wire winding.

2. In a rheostat, the combination of an enclosing housing, an insulating base secured within the same, a resistance support secured to said base and comprising a pair of core 60 plates of a split ring form attached together

in spaced relation, each core plate consisting of an inner rigid core plate and an insulated cover plate, a winding of resistance wire encircling said core plates, and a centrally pivoted arm carrying at its outer end a contact shoe adapted for bearing upon said wire winding. 70

3. In a rheostat, the combination of an enclosing housing, an insulating base secured within the same, a resistance support 75 secured to said base and comprising a pair of core plates of a split ring form attached together in spaced relation, each core plate consisting of an inner rigid core plate and an insulating cover plate having marginal 80 inner and outer flanges, a winding of resistance wire encircling said core plates, and a centrally pivoted arm carrying at its outer end a contact shoe adapted for bearing upon said wire winding. 85

4. In a rheostat, the combination of an enclosing housing, an insulating base, secured within the same, a resistance support secured to said base and comprising a pair of core plates of a split ring form attached 90 together in spaced relation, a winding of resistance wire encircling said core plates, a centrally pivoted and radially extending arm, and a triangular shape contact shoe 95 pivotally mounted on the outer end of said arm and adapted for bearing upon said wire winding.

5. In a rheostat, the combination of an enclosing housing, an insulating base secured within the same, a resistance support 100 secured to said base and comprising a pair of core plates of a split ring form attached together in spaced relation, a winding of resistance wire encircling said core plates, a centrally pivoted and radially extending 105 arm, a triangular shape contact shoe pivotally mounted on the outer end of said arm, and a spring tending to tilt one end of said shoe towards said wire winding.

6. In a rheostat, the combination of an 110 enclosing housing, an insulating base secured within the same, a resistance support secured to said base and comprising a pair of core plates of a split ring form attached together in spaced relation, a winding of 115 resistance wire encircling said core plates, a bridge piece carried by one of the core plates, an operating shaft journaled in said bridge piece in central relation to the core plates, a radial arm attached to said shaft, 120 and a contact shoe pivotally mounted on the outer end of said arm and adapted for bearing on said wire winding.

7. In a rheostat, the combination of an 125 enclosing housing, an insulating base secured within the same, a resistance support secured to said base and comprising a pair of core plates of a split ring form attached together in spaced relation, a winding of resistance wire encircling said core plates, 130

a bridge piece carried by one of the core plates, a journal bushing fixed to said bridge piece in central relation to the core plates, an operating shaft journaled in said bushing and having limited sliding movement therein, a spring tending to slide shaft in a direction towards the aforesaid core plates, a radial arm attached to said shaft, and a contact shoe pivotally mounted 10 on the outer end of said arm and adapted for bearing on the wire winding of the core plates.

8. In a rheostat, the combination of an enclosing housing, an insulating base secured to said base and comprising a pair 15 of core plates of a split ring form attached together in spaced relation, a winding of

resistance wire encircling said plates, a bridge piece carried by one of the core 20 plates, a journal bushing fixed to said bridge piece in central relation to the core plates and having at one end a laterally arranged stop lug, an operating shaft journaled in said bushing and having limited sliding 25 movement therein, a spring tending to slide said shaft in a direction towards the aforesaid core plates, a radial arm attached to said shaft and a contact shoe pivotally mounted on the outer end of said arm and 30 adapted for bearing on the wire winding of the core plates.

Signed at Duluth, Minn., this 25th day of March 1921.

JOSEPH GRANZ.
